FIG. 1.

FIG. 2.

FIG. 4.

FIG. 3.

Inventor

BENJAMIN MICHAILOVSKY

By his Attorney Edwin Lincoln

UNITED STATES PATENT OFFICE.

BENJAMIN MICHAILOVSKY, OF NEW YORK, N. Y.

KEY HOLDER.

Application filed March 19, 1925. Serial No. 16,656.

My invention relates generally to pocket key holders of a type in which a plurality of keys are removably and collapsibly mounted in a handle member.

5 The principal object of my invention is to provide a key holder of this character in which a series of plates are detachably connected together to form a handle to receive and support keys, which may be swung outside of the handle for use, and collapsed therein when the holder is being carried as a pen knife.

One embodiment of the invention is illustratively exemplified in the accompanying 15 drawing, in which:

Figure 1 is a side elevational view of the key holder showing keys in closed and projected positions; Figure 2 is an edge view of the same; Figure 3 is a side view showing 20 the keys collapsed within the handle and one of the plates removed to disclose the inner or mid-plate; and Figure 4 is an edge view of one end of the handle with no keys interposed.

25 Referring to the drawings, 10 designates the handle of the key holder comprising a pair of spaced outside plates 11 and 12 and an intermediate plate 13. Each outside plate is a strip of narrow gauge metal having opposite ends rounded and blending into curved nose portions 14 which project from opposite edges of the plate. The latter plates are further provided with finger recesses 15 disposed in opposite edges mid-way of their length. Adjacent opposite ends of the end plate 11, the latter is provided with transversely projecting spindles 16, integral with the plate at one end and having threaded openings 17 in the free ends. The 30 other end plate 12 is provided with small openings 18 to register with the openings 17 and the plates are secured together by screws 19, which are disposed in the openings 17, and which are provided with heads adapted

to hold the plate 12 in position. The intermediate plate 13 is provided with a straight midportion somewhat narrower than the corresponding section of the side plate so as to allow ample room for finger manipulation in the recesses 15. The plate 13 is further 45 provided with end openings 20 which receive the spindles 16 and outwardly projecting oppositely disposed pins 21, which abut the inside face of the plates 11 and 12 to space the plate 13, and which also act as stops or 50 rests for the keys 22, the heads of the latter being pivotally carried by the projections of the spindles 16 between the plates 11, 12 and 55 13.

In the illustrations the invention is shown 60 as comprising two side plates and one mid-plate to form the handle, while in practice any number of plates may be combined to hold large numbers of keys by simply supplying the end plates 11 with spindles of 65 greater length. To facilitate carrying the key holder, a bale 23 is arranged at one end of the handle.

Having described my invention, what I 70 claim is:

In a pocket key holder, a handle comprising spaced outside plates, one thereof being provided with spindle projections having their free ends bored and threaded, screws 75 disposed in said bores and engaged against the other plate to hold it in position, a mid-plate mounted on said spindles and provided with projections centrally thereof to abut the outer plates and act as a stop for the keys hung on the spindles, the outer edges of the 80 plates being recessed to expose the grooves of the keys, and a bale carried by the screw at one end of the handle.

In testimony whereof, I have signed my name to this specification this 18th day of 85 March 1925.

BENJAMIN MICHAILOVSKY.
